MEANS FOR PROTECTING SHIPS AGAINST
UNDERWATER EXPLOSIONVadim S. Makaroff and Nicholas C. Artsay,
New York, N. Y.

Application December 9, 1942, Serial No. 468,436

2 Claims. (Cl. 114—240)

This invention relates to means and method for protecting ships against underwater explosions and has particular reference to means and methods for building or reinforcing ships in such manner that the effect of explosions as caused by torpedoes or mines is greatly reduced or even entirely suppressed.

This invention has for its object to provide a ship with protecting layers on the underwater portions of its hull, the layers being so constructed as to absorb the energy of an underwater explosion.

The protective layer for the hull, according to our invention, consists of a combination of at least two materials, each of which, if used alone, would not afford sufficient protection. The two materials can be combined in a single unit but they must retain their individual properties, however thoroughly they may be mixed. One example of such material is wet wood which comprises fibrous particles, destructible under action of explosive forces, and water or moisture which acts as a conductant of detonation. Another example is a special form of concrete or similar mouldable composition in which particles of light, destructible material are mixed with cement.

A homogeneous material, if used alone, would not afford the desired protection, even when used in relatively large quantities.

Our invention is more fully explained by way of examples in the accompanying specification and drawing, in which:

Fig. 1 is a fractional sectional view of the hull of a ship in which wet wood is employed as protective material;

Fig. 2 is a similar view of a modified construction also using wet wood;

Fig. 3 is a detail sectional view taken on the line 3—3 of Fig. 1;

Fig. 4 is a fractional sectional view of the hull of a ship in which a special cement or concrete composition is used; and

Fig. 5 is a similar view of a modified ship construction.

In one form of my invention the protective layer for a ship 1 consists of a plurality of superimposed timbers attached to the hull 2 of the ship.

To obtain the best results, the timbers are preferably arranged differently on different portions of the hull. At the middle short timbers 3 are placed vertically, being held at the ends between longitudinally extending I-beams or T-bars 4. Below these vertical timbers there are 55

curved vertically extending T-bars 5, holding the ends of horizontally extending timbers 6. These timbers form the first layer, to which additional layers of vertical timbers, 7, 8, 9, etc. are attached by screws 10. The screws are relatively short joining not more than two timbers so that in the event of an explosion when the outer layers are destroyed, the screws would not pierce the hull plates.

The upper ends of the timbers rest against a horizontal plate 11, supported by brackets 12, and reinforced by channels 15. The lowermost curved portion of the protective covering is built up of filling pieces 13, arranged in convenient lengths. The timbers are enclosed in a thin sheet iron covering 14. A similar covering or sheathing is provided for upper timbers 16, tapering upward toward the hull from the plate 11.

According to our investigations, the wet wood represents a very satisfactory material for protecting the hull against underwater explosions, because such wood actually consists of two materials or substances; the fibrous body, which can be readily crushed and even comminuted by the force of explosion, thereby reducing the pressure and temperature of the gases of explosion, and water or moisture, forming a winding path for the rapid spread of detonation to adjacent portions of wood, thereby greatly increasing the volume of destruction and correspondingly reducing the force, acting on the plates of the hull. With a reasonable thickness of our protective layer it is possible so to reduce the effect of the force of explosion of a one thousand pound charge, for instance, that only a relatively harmless puncture will result in the hull plates, without any harmful effect on other parts of the ship.

The wood must be wet, however, in order to provide the maximum of protection. For this purpose the timbers must not be joined together too tightly, and it is even desirable to leave large wedge-shaped clearances 17 between the timbers as shown in Fig. 3, leaving also a few holes in the sheathing 14 for admitting sea water between the timbers.

The foregoing construction is especially suitable for reinforcing or protecting old or already built ships. For new ships 18 it is preferred to use a simplified construction shown in Fig. 2, the timbers 7, 8, 9, etc. being placed on the recessed hull plates 20, so that the ship's hull can have a single curvature thereby facilitating arrangement of wood protection and of its upper framing. The lower ends of the timbers are trimmed to suit the hull's other curvature. An outer thin

iron sheathing 19 is provided over the timbers to receive paint and to protect the wood against marine borers and barnacles. It need not be water tight.

Good results can be also obtained by using a mouldable material 28 as shown in Fig. 4, by pouring the material into a space between the temporary outer form 21, and the hull proper 22, upper plate 23, and a lower retaining or bilge keel frame 24. Supplementary chambers are formed under the frame 24 in front of a keelson 25, also filled with the same mouldable material 28 for transmitting the compression forces to twin bottom framing and plating.

Any suitable composition can be used for filling the chambers at the sides of the hull, provided the composition consists of at least two distinctly different substances, having the required properties as explained above. We prefer to use for this purpose, however, a special concrete mixture, in which sand and gravel are replaced by a light, destructible material such as kieselguhr, pumice stone, properly sized coke, crushable stone, etc., cement which is used as a binder, serving also as a conductor of the detonation waves. Such a reinforcement is well suited for warships, Fig. 4, representing a diagrammatic section of a battleship 29. Metal reinforcements may be used for imparting greater strength to the moulded material, the reinforcements being in the form of hooked rods 26, locked to the T-bars 4, also interlocked hooked rods 27 extending partly transversely and partly longitudinally.

A satisfactory protection can be also obtained by using a fluid or semi-fluid composition, such as a mixture of heavy tar and coke or heavy tar and small blocks of wood, filling the compartments or chambers between the inner strong wall 22 of the hull and a very light outer hull or "blister" 21. In this case the heavy tar will serve as detonation wave conductant.

Our invention is not restricted to the protection of the sides of the ship but can be used for protecting the bottoms as well.

A relative degree of protection can be also obtained by adding crushable material such as pumice stone in adequate quantity to the water or fuel oil in existing tanks in the ship, in wing compartments or in a double bottom.

The protection as described is readily adaptable also for ships often subject to explosions at some distance from their hulls, for instance submarine boats when attacked with depth charges, also ships subject to aerial bombardment, when many near misses may disable the ships without direct hits.

In this case the blast (sound wave) due to expansion of gas bubble does most of the damage and the interposition of a relatively thin layer of crushable material will absorb the energy of the wave and protect the ship plates behind. The

use for this purpose of wood sheathing is pre-ferred.

The protective material may be placed in compartments 30, 31, and under the bottom 32 of the ship 33, as shown in Fig. 5, behind ordinary empty blisters 34.

The painted sheet iron covering or sheathing for wood or other protective material is intended as a defense against borers and barnacles and can be increased in thickness if saving in weight is not of any great importance. The purpose of such a covering is to prevent the gas at high pressure during the beginning of the second phase from penetrating the wood or other protection laterally thereby subsequently weakening the whole protective structure and its bond with the hull. As certain experiments have indicated, a thin steel plating laid over an elastic or yielding material is not destroyed by the force of explosions because, due to its thinness and flexibility, the plating readily accelerates and transmits detonation waves and gas pressure to the material behind. Thus it is possible to facilitate the lateral expansion of explosion gas from the initial de-pression in the protective layer, directing it outward by the relatively smooth steel surface instead of jagged periphery of the remaining protective material. It appears as if the additional thickness of steel plating over wood or other protective material causes glancing of the expanding gas over the periphery of residual protective material with a consequent reduction of damage to the protective structure and to its backing; small holes can be provided in the plating for allowing access of water to the wood.

It is understood that our means and method for protecting ships against underwater explosions may be further modified without departing from the spirit of the invention as set forth in the appended claims.

We claim as our invention:

1. Means to protect a ship against an underwater explosion comprising a plurality of super-imposed layers of timbers at the side of the hull of the ship; means to fasten each succeeding layer to the preceding layer; and means to support the ends of the timbers, the timbers being disposed with clearances therebetween for admitting water from the outside of the hull.

2. Means to protect a ship against an underwater explosion comprising a plurality of super-imposed layers of timbers at the side of the hull of the ship, said timbers extending in a substantially vertical direction; means to fasten the timbers to the hull, the timbers being provided with clearances therebetween for admitting water thereby maintaining the timbers in a wet state.
